(57) **CLAIM**

The ornamental design for a soil detector, as shown and described.

DESCRIPTION

FIG. 1 is a perspective view of a soil detector showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading and cross-hatching are not features of the design but are utilized to illustrate the surface contours of the soil detector design in the drawings.

The broken lines in the drawings depict portions of the soil detector that form no part of the claimed design.
